UNITED STATES PATENT OFFICE.

GEORGE E. DE GRANGE AND WILLIAM G. GREEN, OF NEW ORLEANS, LA.

CAR-AXLE BOX.

SPECIFICATION forming part of Letters Patent No. 318,879, dated May 26, 1885.

Application filed February 12, 1885. (No model.)

To all whom it may concern:

Be it known that we, GEORGE E. DE GRANGE and WILLIAM G. GREEN, citizens of the United States, residing at New Orleans, Louisiana, 5 have invented new and useful Improvements in Car-Axle Boxes, of which the following is a specification.

Our invention relates to that class of car-axle boxes in which the journal of the axle re-10 volves in a chamber containing the lubricant and a suitable vehicle—such as tow or cotton or other medium—for feeding the lubricant to the journal.

The object of the invention is to provide 15 simple and effective means for excluding dust and grit from the interior of the box, thereby preserving the oil or lubricant in a free and clear condition, so that there will be no ap-20 preciable wear of the journal and the brass or bearing. The invention also has for its object to prevent the loss of oil at the front of the box where, as in ordinary boxes heretofore de-25 vised, the oil is liable to escape through the joints between the cover and the box.

To these ends the invention consists in fit-30 ting a cup-shaped annular flange on the axle of the wheel and providing the rear end of the axle-box with a boss carrying a collar, which fits into or is inclosed by the annular flange on 35 the axle. Said collar bears a packing-ring up- on its outer face, which rests against the bottom of the cup-shaped annular flange, so that the parts thus fitted will effectually prevent the entrance of dust or grit into the oil or journal 40 chamber.

The invention also consists in locating a ver-45 tical division-plate at the front of the oil-cham-ber of the axle-box, said plate extending from near the floor of the chamber up to the under 40 side of the journal of the axle, and being ar-50 ranged at the inlet opening or mouth of the axle-box. The object of said plate is to arrest the outward flow of the oil caused by jolts or concussions when the car is turning curves, or 55 from other causes, thereby preventing the oil from being thrown against the axle-box cover and leaking out through the joints. Said stop- 60 plate does not extend to the bottom of the oil-chamber, and hence the latter can be replen-65 ished with oil by causing the same to flow under the plate.

In the drawings, Figure 1 is a longitudinal

section of a car-axle box embodying our im-55 provements. Fig. 2 is a detail view of the wheel, axle, and cup-shaped flange on said axle. Fig. 3 is a rear view of the axle-box, representing the collar and packing-ring applied thereto.

The reference-numeral 1 designates an axle-60 box, which is made of cast-iron in the form and manner usually employed for this purpose, and is fitted in an appropriate hanger or pedestal, so as to slide up and down as the cus-65 tomary pressure-springs contract or expand. A bearing or box, 2, of brass or other compo-70 sition metal, fits the journal 3 of the axle 4, and is provided on its back with a transverse groove 75 to engage with a rib, 5, on the under surface of the top of the box, so as to prevent said bearing from moving in the direction of the length of the axle. In the front of the box is an open-75 ing, which is closed by a lid or cover, 6, that can be removed or lifted to renew the oil or lubricant and the cotton waste, tow, or other medium for holding the oil and feeding it to the journal.

As shown in the drawings, the upper edge 80 of the cover engages with a recess, 8, formed near the top of the box 1, and its lower edge has an apertured lug, 9, through which is passed a pin or screw, 10, that enters a seat or 85 socket, 11, on the box and holds the cover in position.

At the sides of the opening or mouth of the 85 box are formed guideways for the reception of the detachable plate 12, which, when in posi- 90 tion, bears against the front end of the axle-journal, so as to prevent the longitudinal move- 95 ment thereof.

All the parts above designated are similar to those used in axle-boxes heretofore devised, and form no part of our invention.

At the front of the oil or lubricant chamber 100 and a short distance from the solid front wall, 13, disposed below the mouth or inlet opening, is located a transverse plate, 14, which rises 105 from near the bottom of the oil-chamber to a point immediately below the under side of the journal of the axle. Said plate 14 is generally inclined in an inward direction from the front of the axle-box, and a space or filling cham-110 ber, 20, is thus left between the front wall, 13, and said plate 14. When oil is poured into said space 20, it will flow under the plate 14 into the lubricating-chamber, as will readily be ap-

parent. The chief function of said plate, however, is to prevent the splashing of the oil against the cover or lid of the axle-box, since the oil, when thrown against the plate 12, can 5 seldom overflow the same and leak out at the front of the box.

For the purpose of insuring a dirt or grit proof joint at the rear of the axle-box, we provide the axle with a cup-shaped flange and 10 plate, 15, which are fitted on the axle, so as to move therewith; or, if desired, the annular flange can form an integral part of the car-wheel 16 by being cast on the inner face thereof. On the rear face or wall of the axle-box is 15 formed a hub or boss, 17, which has an outer collar or ring-plate, 18, made of such size as to fit into the cup-shaped flange and plate on the axle, but being smaller than the seat-space in said cup-shaped flange, so that the latter can 20 revolve around the ring-plate 18 without friction against its periphery. The inner face of the ring plate or collar 18 carries an elastic or other suitable packing-disk, 19, which bears against the bottom of the cup-shaped flange 25 and prevents access of dirt and grit to the axle passing through the packing-disk 19, plate 18, and hub 17.

By providing an axle-box with our attach-

ments above fully set forth we effectually guard against the leaking out of the oil through the 30 front and rear of the box, and also prevent the entrance of dirt and grit into the interior of the box, thus preserving the bearings and journals intact for a vastly longer period than is the case with the axle-boxes heretofore known. 35

What we claim is—

1. The combination of the axle-box provided with the hub or boss 17, formed integral with the annular metallic disk 18, with the flexible packing-disk 19, attached directly to the inner 40 face of the metallic disk, the axle, the wheel, and the cup-shaped annular flange 15, substantially as described.

2. The car-axle box provided with the transverse division-plate 14, having its upper and 45 lower horizontal edges terminated, respectively, at a distance from the car-axle and the bottom wall of the box, substantially as and for the purpose described.

In testimony whereof we affix our signatures 50 in presence of two witnesses.

GEORGE E. DE GRANGE.

WILLIAM G. GREEN.
